US0D1017989S

(12) **United States Design Patent** (10) **Patent No.:** **US D1,017,989 S**
(45) **Date of Patent:** **** Mar. 19, 2024**

(54) **SHOE**

(71) Applicant: **Reebok International Limited**,
Altrincham (GB)

(72) Inventors: **Ricardo Vestuti**, Providence, RI (US);
Dennis Gaboriault, Millbury, MA
(US); **Brian Christensen**, Centerville,
MA (US)

(73) Assignee: **Reebok International Limited**,
Altrincham (GB)

(**) Term: **15 Years**

(21) Appl. No.: **29/890,037**

(22) Filed: **Apr. 19, 2023**

Related U.S. Application Data

(63) Continuation of application No. 29/838,805, filed on May 16, 2022, now Pat. No. Des. 987,264, which is a continuation of application No. 29/782,911, filed on May 10, 2021, now Pat. No. Des. 952,302, which is a continuation of application No. 29/700,539, filed on Aug. 2, 2019, now Pat. No. Des. 919,265, which is a continuation of application No. 29/624,520, filed on Nov. 1, 2017, now Pat. No. Des. 859,799.

(57) **CLAIM**

The ornamental design for a shoe, as shown and described.

DESCRIPTION

FIG. 1 is a bottom perspective view of a shoe showing the claimed design;

FIG. 2 is a front view thereof;

FIG. 3 is a rear view thereof;

FIG. 4 is a left side view thereof; and,

FIG. 5 is a bottom view thereof.

The broken lines in the figures show portions of the shoe that form no part of the claimed design.

The dot-dash broken lines in the figures show boundaries that form no part of the claimed design.

1 Claim, 4 Drawing Sheets
